UNITED STATES PATENT OFFICE.

WILLIAM H. HORNE, OF PORTSMOUTH, NEW HAMPSHIRE.

SHANK SUPPORT FOR SHOES.

Application filed December 7, 1921. Serial No. 520,526.

To all whom it may concern:

Be it known that WILLIAM H. HORNE, a citizen of the United States, residing at Portsmouth, in the county of Rockingham 5 and State of New Hampshire, has invented certain new and useful Improvements in Arch Supports for Shoes, of which the following is a specification.

The present invention relates to improvements in arch supports for shoes of that particular variety in which the support is exterior of the shoe and the invention has for an object to provide an adequate support for the arch of the foot without adding 15 materially to the weight of the shoe or detracting from its appearance.

Another object of the invention is to provide an improved external arch support for shoes in which simplicity of construction 20 and economy are characteristic features, and wherein the supporting medium will be firmly attached to the shank of the shoe in such position as to remain substantially hidden from view at all times.

25 A further object of the invention resides in the provision of an arch support constituting a small article of manufacture capable of being shipped and applied to the shoe at small cost and in a manner which will be 30 obvious to the ordinary shoemaker.

With the foregoing and other objects in view, the invention will be more fully described hereinafter, and will be more particularly pointed out in the claims appended 35 hereto.

In the drawings, wherein like symbols refer to like or corresponding parts throughout the several views,

40 Fig. 1 is a side view of a shoe shown with the improved arch support constructed according to the present invention;

Fig. 2 is a bottom plan view of the shoe and support;

Fig. 3 is a perspective view of the frame 45 of the support; and

Fig. 4 is a similar view taken at a slightly different angle with the block in the frame.

Referring more particularly to the drawings, 1 designates generally a shoe of any 50 conventional type in which 2 is the sole, 3 the shank extending beneath the arch of the foot, and 4 the heel.

According to the preferred form of the invention, a block 5 of a suitable material 55 is used to sustain the arch of the foot and is placed on the outside of the shoe in which

position it is found not inconvenient to the wearer's foot nor a source of discomfort as are those arch supports placed within the shoe and coming directly in contact with the 60 foot. The positioning of the support on the exterior of the shoe leaves the interior entirely free and allows that conformation of the shoe interior, which the manufacturer designed to take into the curvature of the 65 foot, to lie in contact with all parts of the same and thus serve to secure that measure of comfort and convenience which a particular style of shoe may by experience be found to have by the wearer; yet in addition to this comfort and convenience, the wearer may at the same time with the external arch support find the additional relief and comfort furnished only where the arch 70 of the foot is directly sustained.

The block 5 is preferably of rubber, for instance of that character of which rubber soles are made, whereby a good tread-wearing surface is provided and at the same time a suitable degree of resiliency is obtained 75 such as is particularly desirable at the arch. The shoe itself is generally made more or less flexible at this point and the use of a rubber block 5 as a support will not defeat the purposes of this flexibility of the shoe, 80 but will form a support of a flexible nature adapted to yield therewith.

According to one form of the invention, the block 5 is supported in a frame of a rectangular construction having horizontal 85 flanges 6 extending about an opening in which the upper portion of the block 5 is fitted. The flanges 6 are perforated as indicated at 7 for receiving nails or other fastenings 8 by which the device as a whole 90 is secured to the shank 3. Tongues 9 extend down from the flanges 6 and are adapted to embrace the sides of the rubber block 5. The flanges 6 and tongues 9 are preferably 95 stamped from a single piece of material for instance sheet metal, and the flanges 9 may be severed or not at their meeting edges, but I prefer that the block 5 be of a tapering construction or a truncated pyramid with its wider basal part lying uppermost and next 100 the shoe.

The tongues 9 are in this case caused to taper to agree with the inclination given the walls of the truncated block. The tongues 9 therefore embrace the walls snugly 110 and the block is wedged tightly therein so that its wide upper portion will prevent the

block from seeking its way downwardly out of the holding frame. It is noted that the block 5 will be protected forwardly by the sole 2 and at its rear by the heel 4, and that it will therefore not be apt to receive strains that would tend to twist it laterally out of the frame, but any strains that are encountered will be absorbed in the rubber block and will not be apt to wrench the block out 10 of the frame.

It will also be appreciated from this construction that, by the removal of the frame from the shoe by withdrawing the fastenings 8, a fresh rubber block may be substituted for a worn one and the device replaced without a great deal of labor and with only 15 inconsiderable expense.

The device is preferably narrower than the shank of the shoe as clearly appears in Fig. 3 to sustain the arch where needed and at the same time to economize on material 20 and to permit of a lateral flexibility of the shoe when walking. The arch support will also tend to make the wearing of the heel 25 more even and will sustain the shank 3 and

assist to preserve the original shape of the shoe.

It is obvious that various changes and modifications may be made in the details of construction and design of the above specifically described embodiment of this invention without departing from the spirit thereof, such changes and modifications being restricted only by the scope of the following claim. 30 35

What is claimed is:

A shank support for application exteriorly to a shoe comprising an attaching plate having a central opening and separated tongues at the marginal edges of the opening, said tongues being turned downwardly from the plate and normally converging toward their free ends, and a block of resilient material larger at its upper end fitted in the opening of the plate and resiliently held by the tongues, said block being constructed and arranged to slip into place through the top of the plate. 40 45

WILLIAM H. HORNE.
